UNITED STATES PATENT OFFICE.

HENRY R. WALKER, OF NOME, TERRITORY OF ALASKA.

SWEEPING-DREDGE.

1,170,581.

Specification of Letters Patent.

Patented Feb. 8, 1916.

Application filed November 17, 1914. Serial No. 872,673.

To all whom it may concern:

Be it known that I, HENRY R. WALKER, a citizen of the United States of America, and a resident of Nome, in the Territory of Alaska, have invented certain new and useful Improvements in Sweeping-Dredges, of which the following is a specification.

This invention relates to dredges, and the main object thereof is to provide such a device whereby it is enabled to sweep "bed rock," either hard or clay, where the water of a stream is not of a prohibitive depth and whereon gold or other placer mineral has been deposited by the action of the water.

A further object is to provide means whereby the sweepings may be drawn to a concentrator or amalgamator, or suitable containing means by suction.

A further object is to provide means whereby the dredging means may be moved over a considerable area in each position of the supporting means therefor.

A further object is to provide means for changing the relationship between the sweep and dredging means at will, as in clearing weeds or other matter away from the latter which might tend to choke the same.

A further object is to provide means for allowing the sweep to move vertically of the supporting means whereby it may accommodate itself to inequalities in the bed of a stream; and further objects are to provide such means which are simple in construction and operation, highly efficient, permit a considerable period of effective operation between movement of the device, as a whole, from one position to another, and which are comparatively inexpensive.

The invention is fully described in the following specification, of which the accompanying drawings form a part, in which the separate parts are designated by the same reference characters in each of the views, and in which:

Figure 1 is a side elevation of a present preferred form of embodiment of the invention; Fig. 2 is a plan view thereof, partially broken away; Fig. 3 is a similar view, still further broken away; Fig. 4 is a section taken on the line 4—4 of Fig. 2; and Fig. 5 is a section taken on the line 5—5 of Fig. 2.

In the drawings forming a part of this application is shown a vehicle frame com-

prising side bars 6 having a platform 7 at one end thereof and mounted upon driving wheels 8 and steering wheels 9, actuated by means of a gear 10 and pinion 11 on a vertical rod 12 having a wheel 13 at its top. The platform 7 supports an engine 14 having a pinion 15 secured to the shaft thereof, Fig. 3, enmeshed with a pinion 16 on a shaft 17 having its bearings in the side bars 6, 60 said shaft also carrying a clutch 18 operable by means of a lever 19, said shaft being longitudinally adjustable in the side bars. Said shaft 17 also carries a sprocket-wheel 20 connected, by means of a chain 21, to a 70 sprocket 22 on a shaft 23 also carrying a gear 24 enmeshed with a gear 25 on a shaft 26 also having a gear 27 thereon enmeshed with a gear 28 carried by the axle 29 of the wheels 8, and it will be seen that the vehicle 75 may thus be moved and steered at will.

Slidable on tracks 30 on the side bars 6 is a frame 31 having a longitudinally arranged rack 32 upon the under side thereof and which is enmeshed with a pinion 33 80 upon a shaft 34 having a bevel pinion 35 thereon enmeshed with a similar pinion 36 upon a shaft 37 and which carries a bevel pinion 38 at its forward end enmeshed with one or the other of two pinions 39 or 40 on 85 a shaft 17 and revoluble therewith, but slidable therewith when moved by means of a lever 40^a, but this is an old and well known form of reversing gear, and it will be seen that the frame 31 may thus be moved longitudinally of the vehicle, forwardly or rearwardly thereof, at will.

The frame 31 carries a supplemental frame 41 thereon and pivoted thereto at 42 whereby it may be swung laterally of the vehicle, and said supplemental frame projects rearwardly of the frame 31 and carries an engine 43 thereon in operative connection with a rotary pump 44 thereon by means of a chain 45, and said pump has an 100 intake pipe or hose 46 having a perforated end 47, and an exhaust pipe 48 leading to an amalgamator 49, which might also be a concentrator or equivalent, and which is geared to the engine 43 by means of a chain 50. 105 The said engine is also geared, by means of a chain 51, with a shaft 52, Fig. 2, having a pinion 53 thereon enmeshed with a gear 54 on a shaft 55 carrying also two reversely arranged bevel pinions 56 and 57 adapted for 110 alternate connection with a pinion 58, by means of a lever 59; the pinion 58 is secured

upon a shaft 60 having, also, a pinion 61 thereon enmeshed with a segmental rack 62 carried upon the frame 31, and it will thus be seen that the frame 41 may be swung on its pivot 42, laterally of the frame 31, in either direction, while the frame 31 may be moved longitudinally of the vehicle, in either direction.

Pivoted at 63, to the frame 41, is a yoke 64 having a pendant 65 pivoted thereto at 66, said yoke being adjustable vertically of the frame 41 by means of a cable 67 and pulleys 68 and 69, Fig. 4, the former of which is carried by a rod 70 normally held in uppermost position by means of a spring 71 within a gauntlet 72, a cleat 73 being provided for said cable; in the lower end of the pendant 65 is a shaft 74 having a brush 75 secured thereto, and said shaft is adapted to be rotated by means of a sprocket 76 thereon, a chain 77, a sprocket 78 on a shaft 79 which serves as the pivot for said pendant, a supplemental sprocket 80 thereon, and a chain 81 connecting said last named sprocket with the engine 43, and it will be seen that the brush 75 may be power driven, and the pendant supporting the same be adjusted vertically of the vehicle, but it will also be observed that the brush and pendant are capable of free vertical movement because of the spring suspension means 71, whereby said brush may accommodate itself to inequalities on the bottom of a stream. The outer end of the hose 46 has a collar 82 thereon, in pivotal connection with a lever 83 pivoted in a block 84 secured on the lower end of a sliding plate 85 within guides 86, said lever having a counter-weight 87 thereon, and a cable 88 connected therewith and led to a fixed cleat 89; it will be seen that the board or plate 85 may be vertically adjusted with respect to the frame 41 and held in adjusted position by means of the counterweight 87, thus moving the open end of the hose 46 accordingly, into or out of operative position, and the lever 83 operates to move the said end of the hose into contact with the brush 75, because of the counter-weight 87, and the perforated end 47 of said hose may thus be cleared of any matter tending to obstruct the free flow of water and sand, gravel, or the like, therethrough to the pump 44 and to the amalgamator 49. It will thus be seen that the device, as a whole, may be moved from place to place; the frame 41 carrying the brush and hose may be moved transversely of the vehicle, and the brush and hose may be independently adjusted laterally of the vehicle.

Copies of this patent may be obtained for five cents each, by addressing the "Commissioner of Patents, Washington, D. C."

ently adjusted vertically of the vehicle and toward or from each other; and the frame 31 carrying the frame 41 may be moved longitudinally of the vehicle, thus enabling dredging of a considerable area of the bottom of a stream in any position of the vehicle; also, because of the formation of the brush, and the manner of suspension thereof, the sand or the like may be swept from between stones or boulders toward the hose end 47, and thus results are rendered possible which have heretofore been impossible, as it frequently occurs that relatively rich deposits are washed into and confined between stones on the bottom of a stream, and this brush arrangement also enables a miner to sweep down to what may be termed "bed rock" beneath the sand or gravel, and this has not heretofore been possible.

While certain details of construction have been shown and described, changes thereover may be made, within the scope of the following claims, without departing from the spirit of the invention, or sacrificing its advantages.

Having fully described the invention, what is claimed as new, and is desired to be secured by Letters Patent, is:—

1. A device of the class described, comprising a platform, a frame movable thereon, a supplemental frame movable on said first named frame, a brush vertically adjustable in said supplemental frame, means for actuating said brush, a suction pipe, and a pump in connection therewith.

2. A device of the class described, comprising a platform, a frame movable thereon, a supplemental frame movable on said first named frame, a brush carried by said supplemental frame, a suction pipe, a pump, means for actuating said brush and pump simultaneously, traction means for said platform, and means for actuating said wheels and for actuating said frames at will.

3. A device of the class described, comprising a platform, a brush adjustable thereon, a suction pipe adjustable thereon, means for actuating said brush, and means for bringing said pipe into contact with said brush.

In testimony whereof I have signed my name to this specification in the presence of two subscribing witnesses.

HENRY R. WALKER.
